UNITED STATES PATENT OFFICE.

EMIL STEFFENS, JR., AND HOMER A. JONES, OF RUTHERFORD, NEW JERSEY.

DESIGN FOR A CIGAR-BAND.

42,786.

Specification for Design.

Patented July 9, 1912.

Application filed April 9, 1912. Serial No. 689,694. Term of patent 3½ years.

To all whom it may concern:

Be it known that we, EMIL STEFFENS, Jr., and HOMER A. JONES, citizens of the United States, residing at Rutherford, Bergen county, New Jersey, have invented a new, original, and ornamental Design for Cigar-Bands, of which the following is a specification, reference being had to the accompanying drawing, forming part hereof.

The figure is a face view of a cigar band, showing our new design.

We claim:

The ornamental design for a cigar band, as shown.

EMIL STEFFENS, JR.
HOMER A. JONES.
